CALCULATING-MACHINE.

1.120,317.

Specification of Letters Patent.

Patented Dec. 8, 1914.

Application filed March 19, 1910, Serial No. 550,396. Renewed May 4, 1914. Serial No. 836,357.

To all whom it may concern:

Be it known that I, OTTO MALCHER, a citizen of the United States, residing at Chicago, in the county of Cook and State of Illinois, have invented certain new and useful Improvements in Calculating-Machines, of which the following is a specification.

In an application of Samuel E. Carlin for United States Letters Patent for improvements in calculating machines, Serial No.

514,447, there is shown and described a plurality of operating shafts for the number bearing members of the totalizers, each of which shafts is provided with a series of 15 nine operating gears. Power shafts are also provided for transmitting motion to the operating shafts and these power shafts are each provided with selector mechanisms individual to the gears on the operating shafts, 20 whereby a variable movement may be imparted to the respective operating shafts. These selector mechanisms are in turn controlled by actuating keys individual to the selector mechanisms, which construction and 25 arrangement necessitates, in the exemplification of the invention set forth in the said application, eighty-one operating keys and a corresponding number of selector mechanisms and gears for controlling the operation 30 of the number bearing members.

It is the primary object of the present invention to simplify this structure by dispensing with a number of the parts and at the same time provide a construction where- 35 by the operating gears may be arranged compactly in a minimum space, and to this end there is provided a series of gears for each of the power shafts for imparting a variable movement to the respective operating 40 shafts of the number bearing members of the totalizer and a traveling actuating gear on each of the operating shafts, which gear is common to the gears of the series on the respective power shafts.

45 A further object is to provide improved selector mechanisms for shifting and positioning the traveling gears with relation to the gears on the respective power shafts.

A further object is to provide improved 50 means for locking the actuated key of any one series in its actuated position and the remaining keys of the respective series against operation when one of the series is actuated.

55 A further object is to provide improved means for automatically restoring the actu-

ated key to its normal position and for shifting the respective traveling gears to normal or inactive positions.

A further object is to provide improved 60 means common to all of the keys for manually and simultaneously releasing all of the actuated keys, and also improved means individual to the series of keys for manually releasing the actuated key of the re- 65 spective series.

A further object is to provide improved means common to the keys of the respective series for locking or holding the traveling gears in their normal or inactive position 70 and for releasing the gears by the operation of any one key of the respective series of keys to permit the gears to be correspondingly adjusted to the proper position by the respective selector mechanisms when the lat- 75 ter are actuated by the keys.

A further object is to provide mechanism of this character which will be simple, durable and cheap in construction, compact in arrangement, and effective and efficient in 80 operation.

To the attainment of these ends and the accomplishment of other new and useful objects as will appear, the invention consists in the features of novelty in the con- 85 struction, combination and arrangement of the several parts hereinafter more fully described and claimed and shown in the accompanying drawings constituting an embodiment of the invention, in which— 90

Figure 1 is a longitudinal sectional view of the keyboard and a portion of the machine, constructed in accordance with the principles of this invention. Fig. 2 is a detail perspective view of a portion of the setting 95 mechanism slide bar. Fig. 3 is a sectional view on line 3—3 of Fig. 4. Fig. 4 is a horizontal sectional view on line 4—4 of Fig. 1. Fig. 5 is a detail plan view partly broken away of the mechanism for simultaneously 100 returning all of the actuated keys. Fig. 6 is a detail perspective view of a portion of one of the members for locking the traveling gears in their inactive positions. Fig. 7 is a detail perspective view of a portion of the 105 stem on one of the keys. Fig. 8 is a sectional view on line 8—8 of Fig. 1. Fig. 9 is a plan view of a portion of the keyboard.

Referring more particularly to the drawings and in the present exemplification of 110 the invention, the numerals 15 designate suitable supports, which are spaced from

each other and mounted upon the base of the machine. Journaled in these supports 15 are a plurality of power shafts 16, preferably nine in number, one for each of the 5 operating shafts 17, and which latter shafts are journaled in suitable supports, preferably the supports 15, and are arranged in a plane above the shafts 16. One of these power and operating shafts 16, 17 is provided for each of the number bearing members 18 of the totalizers, and the operating shafts 17 are connected to shafts 19, which latter are arranged in the same plane as the respective shafts 17 by means of a pawl and 10 ratchet connection 20, 21, so that when the shafts 17 are rotated in a manner to be hereinafter set forth, the respective shafts 19 will be rotated to convey motion to the number bearing members 18 of the totalizers 15 through the medium of a train of connecting 20 gears 22.

Journaled in suitable supports and preferably in the same plane with the power shafts 16 is a running shaft 23 (see Fig. 4), and 25 another shaft 24 parallel with the shaft 23 is provided. A shaft 25 is arranged to extend transversely across the ends of the shafts 16 and is journaled in suitable supports such as brackets 26, and a plurality 30 of gears 27 are provided on this shaft 25, and which gears mesh with gears 28 on the respective power shafts 16. The shaft 25 is also provided with a gear 29, which meshes with a gear 30 on the shaft 24, by 35 means of which the shaft 25 is rotated from the shaft 24. This shaft 24 receives its motion from the running shaft 23 by means of a gear 31, which is mounted loosely upon the running shaft 23. A disk or member 40 32 is also mounted loosely upon the running shaft 23 and is connected with the gear 31. A star or toothed member 33 is secured fast to the shaft 23 for rotation therewith, and a pawl 34 is pivotally supported by the disk 45 or member 32 which cooperates with the star or toothed wheel 33. An elastic member, such as a spring 35 is provided which tends normally to hold the pawl 34 in engagement with the star wheel to lock the gear 31 for rotation with the shaft 23. A gear 36 is secured to the shaft 24 for rotation therewith and meshes with the gear 31. When the gear 31 is locked to the shaft 23 for rotation therewith, it will be apparent 50 that this motion will be imparted to the shaft 24 through the medium of the meshing gears 31, 36, and when the gear 31 is released and unlocked from its shaft 23 the shaft 24 will remain idle. An operating 55 key having a stem 37 is provided for controlling this connection between the shafts 23 and 24, and this stem is connected to an arm 38, which is adapted to engage a shoulder 39 on the dog 34 to hold 60 the latter out of operative position 65

with respect to the star or tooth wheel 33. When the stem 37 is depressed, to release the dog 34, the power shafts 16 will be set in motion and will continue to rotate as long as the stem 37 is depressed. 70 If the stem 37 should be depressed sufficiently to release the dog 34 and then immediately released, the arm 38 would assume a position so that when the shaft 23 is completing its revolution, the arm would engage the shoulder 39 of the dog and automatically unlock the gear 31. The specific construction and operation of the above-referred to parts, however, form no part of the present invention, but constitute a portion of the subject-matter of the application above referred to. The present invention is designed to be associated with this mechanism and comprises a plurality of mutilated gears 40 on each of the power 75 shafts 16. These gears are preferably nine in number and are secured together in any desired or suitable manner, and are preferably arranged adjacent one end of their respective power shafts 16. The gears are 80 provided respectively with a different number of teeth from 1 to 9, and are arranged so that the number of teeth will progress successively from one end to the other end of the respective series. The gears 40 on 85 adjacent power shafts are arranged in staggered relation with respect to each other, that is, the gears on one shaft are preferably arranged adjacent one end of one shaft, while gears on the next adjacent shaft are 90 arranged on the opposite end of the latter shaft so that the shafts 16 may be arranged in close proximity to each other without materially increasing the width of the mechanism. The gears of each of the series 95 100 are secured to their respective shafts and to each other for simultaneous rotation, and a traveling gear 41 is mounted upon each of the shafts 17. These gears 41 are secured to their respective shafts 17 for rotation 105 therewith and for adjustment longitudinally on the shaft by means of a key and feather connection 42, and the gears 41 are also arranged in staggered relation with respect to 110 each other so that they will move adjacent 115 their respective gears 40. The gears 41 are adapted to be moved for any desired distance on the shafts 17, so as to position them with respect to the gears 40 to be engaged by the respective gears when the power 120 shafts 16 are rotated to impart a degree of rotation to the operating shafts 17 corresponding to the number of teeth on the respective gears 40, with which the traveling 125 operating gear 41 meshes.

Each of the gears 41 is adapted to be positioned and shifted by means of a series of keys 43, nine of which keys are provided in each of said series. Selector mechanisms are provided for each of the gears 41 and 130

comprise a setting member slide bar 44, which is provided with an elongated slot 45 extending longitudinally of and for substantially the entire length of the bar. Recesses 46 are provided in the bar, which open through the edges of the slot 45 and have communication with the slot. These recesses 46 are arranged in staggered relation with respect to each other for a purpose to be hereinafter set forth. The bar is also provided with recesses 47, which also open through the sides of the slot 45 and have communication therewith. These recesses 47 are preferably formed by cutting out a portion of the material of which the bar is formed and depressing the cut-out portion to form depending lips 48, one of which lips is arranged adjacent to and cooperates with each of the recesses 46. The forward end 20 of each of the bars 44 is preferably reduced as at 49, and extends through a suitable guide 50, and the forward extremities of the ends 49 are bent upwardly as at 51 to form a handle 52 at the extremity thereof, and 25 which handles project through slots 53 in the top 54 of the casing for the mechanism. The rear ends of the bars 44 are supported in any suitable manner, but preferably by means of fastening devices 55, preferably in 30 the form of headed bolts which project through slots 56 formed by the cut-away portions in the edges of adjacent bars.

Each of the keys 43 is provided with a stem 57, and these stems pass through the top 54 of the casing of the machine and also project through the slot 45 in the respective bars 44. Each stem 57 is provided with a laterally projecting pin 58 which extends over the top of the bar and the projections 40 on the stems extend alternately from opposite sides of the stems. A guide 59 may also be provided through which the stems 57 of the keys 43 pass to assist in supporting and guiding the stems, and an elastic member 60 is provided for each of the bars 44. One end of the elastic member is secured as at 61 to the bar and the other extremity is anchored as at 62 to a fixed support, preferably the guide 59. The bar 44 is adapted to be reciprocated in a manner to be hereinafter set forth and constitutes the selector mechanism for positioning the gear 41 with relation to the respective gears 40. In order to accomplish this result, the gears 41 are secured by means of yokes 63 to the respective bar 44, so that when the bar is longitudinally moved or adjusted the gears 41 will be correspondingly adjusted and the degree of adjustment of the bar 44 will be controlled by the respective keys 43 of the respective series. The bar 44 is adapted to be held in such a position with respect to the stems 57 of the keys that the recesses 46, when the keys are in an inactive or normal position, will stand below the pins or pro-

jections 58 on the respective stems 57, so that when a key is depressed the pins or projections thereon will pass through the respective recesses 46 until the pin stands below the bar. When the pin has assumed this position, the elastic member 60 will operate to move the bar 44 longitudinally and in such a direction that the respective depending lip or projection 48 will engage the pin or projection and arrest the movement of the bar. When the bar is thus shifted, the gear 41 will be shifted and by the time the depending lip or projection 48 engages the pin 58 of an actuated key the gear 41 will have been correspondingly adjusted so that it will be in a position to mesh with the gear of the series 40 which corresponds with the number of the key actuated.

In order to properly position or hold the bar 44 so that the recesses 46 will stand below the pins or projections 58 to receive the latter, a locking member 64 is provided for each series of keys. This locking member may be of any desired or suitable construction, but preferably comprises a bar or member as shown, the extremities 65 of which are bent at an angle to the body portion of the bar, and preferably inclined to one side thereof to form yokes which are pivotally supported upon the respective operating shafts 17 by means of the shafts passing through suitable apertures 66 in the bent extremities 65. Collars 67 may be provided on the shafts 17 and on each side of one of the ends 65 of the yoke for preventing the locking bar from moving longitudinally on the shaft.

Suitable elastic members 68, such as springs or the like, may be provided for normally holding the locking bars or members 64 into the path of movement of the ends of the stems 57 of the respective series of keys 43. These elastic members are secured by one extremity in any suitable manner to the bar 64, and the other extremities thereof are anchored to suitable fixed supports, preferably the guide 59. An elastic member 69 may be provided for each of the keys, and these members surround the stems with one extremity resting upon the guides 59 and the other extremities engaging a pin or shoulder 70 on the stem. The normal tendency of these elastic members 69 is to elevate the keys 43 and to hold them in their normal or inactive positions with the pins or projections 58 on the stems elevated above the bars 44. When the keys 43 are in an inactive or normal position, the bars 44 are in the positions shown in Figs. 1 and 4 of the drawings, that is to say, in their extreme forward positions, with the elastic members 60 under tension. Any suitable means may be provided for holding the bars in this position, and a suitable and efficient means for accomplishing this result comprises a pro-

70

130

jection 71 on each of the bars or members 64. These projections 71 may be formed in any desired manner, preferably by cutting out a portion of the material of which the 5 bar is formed and bending the cut-out portion at an angle to the body portion of the bar. The bar or member 44 is provided with a depending lip or projection 72, and the projection 71 is so arranged as to stand 10 within the path of movement of the projection 72 on the bar or member 44 when the latter is moved by the tension of the elastic member 60 and the locking bar 64 is in its normal position and resting against the ends 15 of all of the stems 57 of the respective series of keys 43.

It is thought that the operation of this portion of the mechanism will be clearly understood, but briefly stated it is as follows: 20 When the parts are in their normal or inactive positions, as shown in Figs. 1 and 4 of the drawings, the setting mechanism slide-bars 44 of the selector mechanisms will be normally held in their extreme forward positions and the locking bars or members 64 will be elevated by the elastic members 66, so that the end of the stems 57 of all of the keys 43 will rest thereon and the bars 44 will be held in their extreme forward positions 25 by means of the projections 72 thereon engaging the projections 71 on the respective bars or members 64. At the same time the operating gears 41 of the operating shafts 17 will be held in their extreme positions 30 and adjacent the mutilated gear having the lowest number of teeth or the gear having one tooth, but out of mesh therewith. Whenever one of the keys of any series is depressed, the first operation will be to rock 35 the locking bar or member 44 about the shaft 17 so as to move the projections 71 out of the path of movement of the projections 72, after which the elastic member 60 will exert its tension upon the bar 44 to shift the latter longitudinally. Before the elastic member 60 acts and just before the projection 40 71 passes out of engagement with the projection 72, the pin 58 on the stem 57 on the actuated key will pass through the recess 45 46 to the under side of the bar 44. The elastic member 60 will then exert its tension on the bar 44 to shift the same longitudinally and the bar will continue to move until the pin or projection 58 is engaged by one of the 50 depending lips or projections 48 on the bar. This will arrest the movement of the bar under the tension of the elastic member 60. During the movement of the bar 44 under the tension of the elastic member, the gear 41 will be correspondingly shifted until it 55 assumes a position adjacent the gear of the member 40 corresponding to the key which has been actuated, and when the movement of the bar 44 is arrested by the lip or projection 48 engaging the pin 58 the gear 41 will

be held in proper position. After the gear 41 has been thus set, the operator may then actuate the key controlling the stem 37 for locking the gear 31 to the shaft 23 to impart motion from the shaft 23 to shaft 24, and 70 which motion will in turn be imparted to the shaft 25, and from the shaft 25 to the shafts 16. When these power shafts 16 are rotated, the respective series of gears 40 will be rotated and the gear 41 will be rotated a number of steps to correspondingly rotate the shafts 17 and ultimately the number bearing 18 of the totalizer, a number of steps equal to the number of teeth on the mutilated gear of the series 40, with which the gear 41 80 meshes. Just at the completion of one complete revolution of the shafts 16 the arm 38 will trip the dog 34 to unlock the gear 31 from the shaft 23. This operation may be repeated as often as desired. When the selector mechanism or slide-bar 44 has been longitudinally adjusted after one of the keys has been actuated, the recesses 46 on all of the other keys will be moved away from the respective pins 58, and when thus adjusted the actuated key will be locked in its actuated position and all of the remaining keys of the same series will be locked against operation until the actuated key has been restored to its normal position. 95

It is necessary after one key of a series has been actuated to return the key to its normal position and also the gear 41 to its normal position before another key can be actuated. Any suitable means may be provided for thus releasing and returning the parts to their normal position. A suitable and efficient means for accomplishing this purpose will now be described. 100

In order to automatically return all of the 105 keys which have been actuated, there is provided a bar or rod 71^a, which is supported for pivotal movement by means of arms 72^a, and these arms are pivotally supported preferably upon the shaft 25. These arms 110 72^a are provided with a projection 73, which extends below the shaft 25 and is adapted to be engaged by a cam 74, which latter is rotatably mounted upon a shaft 75 (see Fig. 1), and a gear 76 is provided for rotating the cam 74, which gear meshes with a gear 77 on the shaft 25. The gear 77 is mounted loosely upon the shaft 25 and is provided with a clutch face 78 with which a clutch member 79 cooperates, and this clutch member 79 is keyed to the shaft 25 for rotation therewith. A lever 80, which extends through the top 54 of the casing of the machine, is provided for shifting the clutch member 79. When the clutch member 79 115 is in engagement with the clutch face 78 of the gear 77 the latter will be locked to the shaft 25, and when so locked will impart rotation to the gear 76. As this gear 76 rotates the cam 74 will rotate and engage the 120 125 130

projection 73 on the arm 72^a to rock the bar 71^a to move the latter into engagement with a lip or projection 81 which depends from the forward end 49 of the bars 44. As the 5 bar 71^a is rocked, all of the bars 44 will be drawn forwardly so as to create a tension on the elastic member 60. A continued rotation of the cam 74 will permit the bar 71^a to be returned to its normal position by 10 means of an elastic member or spring 72^b. As the bars 44 are drawn forwardly, the elastic members 68 will return the locking bars 64 to their normal positions so that the 15 projections 71 thereon will be in position to be engaged by the projections 72 on the bars 44.

It will be apparent that the keys in any one series may be released without releasing the remaining actuated keys of the other 20 series by simply sliding the bars 44 forwardly by grasping the handle 52 of the respective bars, and this may be accomplished without shifting the clutches 79. Suitable mechanisms may also be provided for manually 25 releasing all of the keys which have been actuated, and such mechanism may comprise a bar or plate 82, which is provided with elongated slots 83, through which slots suitable fastening devices 84 pass. 30 This bar or member 82 is preferably supported from the top 54 of the casing, and is provided with a handle 85 which operates in a slot 86 in the top of the casing and extends above the casing. Elastic members 35 87 are provided for normally holding this bar or member 82 in a retracted position. In operation when any of the keys have been actuated, the handle 52 of the respective bars 44 will assume a 40 position in close proximity to the bar or member 82, and all that is necessary in order to manually and simultaneously release all of the actuated keys, is to grasp the handle 85 and draw the bar or member 82 forwardly 45 against the tension of the elastic members 87, and this will simultaneously adjust the members 44.

In order that the invention might be 50 fully understood, the details of the foregoing embodiment thereof have been thus specifically described but

What is claimed as new is—

1. In a calculating machine, the combination of a pair of shafts, a series of gears 55 connected with one of the shafts for imparting a variable movement to one of the shafts, a gear connected with the other shaft and coöperating with the first said gears, one of the said gears and the said series of 60 gears being relatively movable with respect to the other, keys, selector mechanism controlled by the keys for controlling such relative movement, said selector mechanism embodying a sliding slotted member through 65 which the keys pass, and means on the keys

coöperating with the said slotted member for locking the actuated key in its actuated position.

2. In a calculating machine, the combination of a pair of shafts, a series of gears 70 connected with one of the shafts for imparting a variable movement to one of the shafts, a gear connected with the other shaft and coöperating with the first said gears, one of the said gears and the said series of gears 75 being relatively movable with respect to the other, keys, selector mechanism controlled by the keys for controlling such relative movement, and means coöperating with the selector mechanism for locking the actuated key in its actuated position and for locking the unactuated keys 80 against actuation.

3. In a calculating machine, the combination of a pair of shafts, a series of gears 85 connected with one of the shafts for imparting a variable movement to one of the shafts, a gear connected with the other shaft and coöperating with the first said gears, one of the said gears and the said series of gears 90 being relatively movable with respect to the other, selector mechanism for controlling such relative movement, and keys for controlling the selector mechanism, said keys being provided with shoulders, said selector 95 mechanism embodying a slotted member and said slotted member having slots individual to the keys, the shoulders on the keys being adapted to pass through the respective slots and with which shoulders the slotted member 100 coöperates to lock the actuated key.

4. In a calculating machine, the combination of a pair of shafts, a series of gears connected with one of the shafts for imparting a variable movement to one of the shafts, 105 a gear connected with the other shaft and coöperating with the first said gears, one of the said gears and the said series of gears being relatively movable with respect to the other, keys, selector mechanism controlled 110 by the keys for controlling such relative movement, and a shoulder on the keys coöperating with the selector mechanism for locking the actuated key in its actuated position and for locking the unactuated keys 115 against actuation.

5. In a calculating machine, the combination of a pair of shafts, a series of gears connected with one of the shafts for imparting a variable movement to one of the shafts, a gear connected with the other shaft and coöperating with the first said gears, one of the said gears and the said series of gears 120 being relatively movable with respect to the other, selector mechanism for controlling such relative movement, keys for controlling the selector mechanism, means coöperating with the selector mechanism for locking the actuated key in its actuated position, and additional means operating toward 125 130

the end of the cycle of operation of one of the said shafts for automatically actuating the selector mechanism to release the said key.

- 5 6. In a calculating machine, the combination with a pair of shafts, a series of gears connected with one of the shafts for imparting a variable movement to one of the shafts, a gear connected with the other shaft
 10 and coöperating with the first said gears, one of the said gears and the said series of gears being relatively movable with respect to the other, selector mechanism for controlling such relative movement, keys for
 15 controlling the selector mechanism, means coöperating with the selector mechanism for locking the actuated key in its actuated position, additional means operating toward the end of the cycle of operation of one of
 20 the said shafts for automatically actuating the selector mechanism for restoring the latter to normal position and for releasing the actuated key, and means for controlling the last said means at will.
 25 7. In a calculating machine, the combination of a plurality of operating shafts, selector mechanisms individual to the shafts for controlling the rotation thereof, a series of keys individual to each of the selector
 30 mechanisms for controlling the latter, said selector mechanism also serving to lock the actuated key of the respective series in its actuated position, and means operating toward the end of the cycle of operation of
 35 one of the said shafts for automatically and simultaneously actuating all of the selector mechanisms for releasing all of the actuated keys.
 8. In a calculating machine, the combination of a plurality of operating shafts, selector mechanisms individual to the shafts for controlling the rotation thereof, a series of keys individual to each of the selector mechanisms for controlling the latter, said
 40 selector mechanisms also serving to lock the actuated key of the respective series in its actuated position, means operating toward the end of the cycle of operation of one of the said shafts for automatically and
 45 simultaneously actuating all of the selector mechanisms for releasing all of the actuated keys, and means for controlling the last said means at will.
 50 9. In a calculating machine, the combination of a plurality of operating shafts, selector mechanisms individual to the shafts for controlling the rotation thereof, a series of keys individual to each of the selector mechanisms for controlling the latter, said
 55 selector mechanisms also operating to lock the respective actuated keys in their actuated positions, means individual to the selector mechanisms for manually actuating the latter to release the respective keys and
 60 for manually restoring said mechanisms to
 65

normal positions, and additional means common to all of the selector mechanisms for manually and simultaneously restoring all of the keys and the selector mechanisms to normal positions.

- 70 10. In a calculating machine, the combination of a plurality of operating shafts, selector mechanisms individual to the shafts for controlling the rotation thereof, a series of keys individual to each of the selector mechanisms for controlling the latter, said selector mechanisms also operating to lock the respective actuated keys in their actuated positions, means individual to the selector mechanisms for manually actuating the latter to release the respective keys and for manually restoring said mechanisms to normal positions, and additional means common to all of the selector mechanisms for automatically and simultaneously restoring all of the keys and the selector mechanisms to normal positions.

- 75 11. In a calculating machine, the combination of a plurality of operating shafts, selector mechanisms individual to the shafts for controlling the rotation thereof, a series of keys individual to each of the selector mechanisms for controlling the latter, said selector mechanisms also operating to lock the respective actuated keys in their actuated positions, means individual to the selector mechanisms for manually actuating the latter to release the respective keys and for manually restoring said mechanisms to normal positions, additional means common to all of the selector mechanisms for automatically and simultaneously restoring all of the keys and the selector mechanisms to normal positions, and means for controlling the last said means at will.

- 80 12. In a calculating machine, the combination of a pair of shafts, a series of gears connected with one of the shafts for imparting a variable rotation to one shaft, a gear connected with the other shaft and coöperating with the first said gears, one of the said gears and the said series of gears being relatively movable with respect to the other, selector mechanism for controlling such relative movement, means for locking the selector mechanism and the gears in inoperative relation, and a series of keys for controlling the selector mechanism and for actuating the said locking means to release the said mechanism.

- 85 13. In a calculating machine, the combination of a pair of shafts, a series of gears connected with one of the shafts for imparting a variable rotation to one shaft, a gear connected with the other shaft and coöperating with the first said gears, one of the said gears and the said series of gears being relatively movable with respect to the other, selector mechanism embodying a sliding slotted member for controlling such relative

- movement, means for locking the selector mechanism and the gears in inoperative relation, a series of keys passing through the slotted members for controlling the selector mechanism and for actuating the said locking means to release the said mechanism, and means for automatically rendering the said locking means active.
14. In a calculating machine, the combination of a pair of shafts, a series of mutilated gears connected with one of the shafts, a traveling gear on the other shaft and co-operating with and movable relatively to the mutilated gears, selector mechanism including a slotted slideable member for shifting the traveling gear and to which the said gear is connected, said member also having openings therethrough communicating with the slot, means for locking said member against operation, actuating keys for releasing and controlling the said member, one of said keys being disposed adjacent each of said openings, and a shoulder on each of the keys adapted to pass through the respective openings.
15. In a calculating machine, the combination of a pair of shafts, a series of mutilated gears connected with one of the shafts, a traveling gear on the other shaft and co-operating with and movable relatively to the mutilated gears, said selector mechanism including a slotted slideable member for shifting the traveling gear and to which the said gear is connected, said member also having openings therethrough communicating with the slot, means for locking said member against operation, actuating keys for releasing and controlling the said member, one of said keys being disposed adjacent each of the said openings, and a shoulder on each of the keys adapted to pass through the respective openings, the said openings in the member being adapted to be displaced with respect to the said shoulders when the member is released for locking all of the keys of the series.
16. In a calculating machine, the combination of a pair of shafts, a series of mutilated gears connected with one of the shafts, a traveling gear on the other shaft co-operating with the mutilated gears and movable relatively thereto, selector mechanism embodying a slideable member to which the traveling gear is connected for adjustment thereby, said member being provided with a series of openings passing therethrough, a series of keys having stems for controlling the degree of movement of the member, a shoulder on each of the stems adapted to pass through the respective openings in the member, and means for moving the member when released to displace the openings therein with respect to the said shoulders for locking all of the keys of the series when one of the series is actuated.
17. In a calculating machine, the combination of a pair of shafts, a series of mutilated gears connected with one of the shafts, a traveling gear on the other shaft co-operating with the mutilated gears and movable relatively thereto, selector mechanism comprising a slideable member to which the traveling gear is connected for adjustment thereby, said member being provided with a series of openings passing therethrough, a series of keys having stems, projections on the key stems adapted to pass through the respective openings in the member, means for moving the member, and means on the member co-operating with the projections on the respective keys for limiting the movement of said member.
18. In a calculating machine, the combination of a pair of shafts, a series of mutilated gears connected with one of the shafts, a traveling gear on the other shaft co-operating with the mutilated gears and movable relatively thereto, selector mechanism comprising a slideable member to which the traveling gear is connected for adjustment thereby, said member being provided with a series of recesses passing therethrough, a series of keys having stems, projections on the key stems adapted to pass through the respective recesses in the member, means for moving the member, means on the member co-operating with the projections on the respective keys for limiting the movement of said member, and means also on the member for returning the member to adjust the traveling gear and for releasing the actuated key.
19. In a calculating machine, the combination of a pair of shafts, a series of mutilated gears connected with one of the shafts, a traveling gear on the other shaft and movable relatively to the first said gears, selector mechanism including a slideable member, means for locking the member against movement, said member being provided with a plurality of openings therethrough, key stems adapted to release the member, said stems being provided with projections adapted to pass through the respective openings as the member is released, means for shifting the member when released, and means co-operating with the projections on the stems for arresting the movement of the member and for controlling the degree of movement of said member.
20. In a calculating machine, the combination of a pair of shafts, a series of mutilated gears connected with one of the shafts, a traveling gear on the other shaft, and movable relatively to the first said gears, selector mechanism including a slideable member, means for locking the member against movement, said member being provided with a plurality of openings therethrough, key stems adapted to release the

- member, said stems being provided with projections adapted to pass through the respective openings as the member is released, means for shifting the member when released, means cooperating with the projections on the stems for arresting the movement of the member and for controlling the degree of movement of said member, and means for returning the member to release 10 the actuated key.
21. In a calculating machine, the combination of a pair of shafts, mutilated gears on one of the shafts, a traveling gear on the other shaft and movable relatively to the 15 first said gears, selector mechanism including a slidable member with which the traveling gear is connected for adjustment thereby, a pivoted member for locking the first said member against movement, actuating keys for rocking the locking member to release the first said member, cooperating means on the slidable member and keys for controlling and limiting the movement of 20 said member and for locking all of the keys 25 when one key is actuated, and means for moving the slidable member when released to adjust the traveling gear to operative position.
22. In a calculating machine, the combination of a pair of shafts, mutilated gears on one of the shafts, a traveling gear on the other shaft and movable relatively to the 30 first said gears, selector mechanism including a slidable member with which the traveling gear is connected for adjustment thereby, a pivoted member for locking the first said member against movement, actuating keys for rocking the locking member to release the first said member, cooperating means on 35 the slidable member and keys for controlling and limiting the movement of said member, and for locking all of the keys when one key 40 is actuated, and means for automatically moving the slidable member when released 45 to adjust the traveling gear to operative position.
23. In a calculating machine, the combination of a pair of shafts, mutilated gears on one of the shafts, a traveling gear on the 50 other shaft and movable relatively to the first said gears, selector mechanism including a slidable member with which the traveling gear is connected for adjustment thereby, a pivoted member for locking the first said member against movement, actuating keys for rocking the locking member to release the first said member, cooperating means on the slidable member and keys for controlling and limiting the movement of 55 said member, and for locking all of the keys 60 when one key is actuated, means for moving the slidable member when released to adjust the traveling gear to operative position, and means for releasing said member to release 65 the actuated key.
24. In a calculating machine, the combination of a pair of shafts, a series of mutilated gears on one of the shafts, a traveling gear on the other shaft and movable relatively to the first said gears, selector mechanism including a slidable slotted member to which the traveling gear is connected for adjustment thereby, key stems passing through the slot, a shiftable member for normally locking the slidable member 70 against movement and the traveling gear out of operating position, said shiftable member being adapted to be engaged and shifted by the key stems, means for moving the slidable member when thus released, and 75 cooperating means on the member and stems for controlling the degree of movement of the sliding member.
25. In a calculating machine, the combination of a pair of shafts, a series of mutilated gears on one of the shafts, a traveling gear on the other shaft and movable relatively to the first said gears, selector mechanism including a slidable slotted member to which the traveling gear is connected for 80 adjustment thereby, key stems passing through the slot, said member being provided with a plurality of spaced recesses 85 communicating with the slot and said stems being each provided with a projection for the respective adjacent recesses, a shiftable member tending normally to lock the slidable member against movement and to hold the said recesses in positions to receive the 90 projections and adapted to be engaged and shifted by the stems, means for moving the slotted member when released, and means on the slidable member adapted to engage the 95 projections on the respective stems to control and limit the movement of the last 100 said member.
26. In a calculating machine, the combination of a pair of shafts, a series of mutilated gears on one of the shafts, a traveling gear on the other shaft, and movable relatively to the first said gears, selector mechanisms including a slidable slotted member to which the traveling gear is connected for adjustment thereby, key stems passing through the slot, said member being provided with a plurality of spaced recesses 110 communicating with the slot and said stems being each provided with a projection for the respective adjacent recesses, a shiftable member tending normally to lock the slidable member against movement and to hold the said recesses in positions to receive the 115 projections and adapted to be engaged and shifted by the stems, means for moving the slotted member when released, means on the slidable member adapted to engage the 120 projections on the respective stems to control and limit the movement of the last said member, and a handle on the slidable member for moving the latter in the opposite 125 direction.

direction at will to release an actuated key and for moving the traveling gear into inactive position.

27. In a calculating machine, the combination of a pair of shafts, a series of gears connected with one of the shafts for imparting variable movement to one of the shafts, a traveling gear connected with the other shaft and coöperating with the said series of gears, selector mechanism for shifting the traveling gear, said mechanism including a slideable member with which the gear is connected, keys for controlling the selector mechanism, and means operatively related to one of the shafts for automatically returning the sliding member to shift the gear to an inoperating position.

28. In a calculating machine, the combination of a pair of shafts, a series of gears connected with one of the shafts for imparting variable movement to one of the shafts, a traveling gear connected with the other shaft and coöperating with the said series of gears, selector mechanism for shifting the traveling gear, said mechanism including a slideable member with which the gear is connected, keys for controlling the selector mechanism, means operatively related to one of the shafts for automatically returning the sliding member to shift the gear to an inoperating position, and means for controlling the last said means at will.

29. In a calculating machine, the combination of a pair of shafts, a series of gears connected with one of the shafts for imparting variable movement to one of the shafts, a traveling gear connected with the other shaft and coöperating with the said series of gears, selector mechanism for shifting the traveling gear, said mechanism including a slideable member with which the gear is connected, keys for controlling the selector mechanism, means operatively related to one of the shafts for automatically returning the sliding member to shift the gear to an inoperating position, and means including clutch mechanism for controlling the last said means at will.

30. In a calculating machine, the combination of a pair of shafts, a series of gears connected with one of the shafts for imparting variable movement to one of the shafts, a traveling gear connected with the other shaft and coöperating with the said series of gears, selector mechanism for shifting the traveling gear, said mechanism including a slideable member with which the gear is connected, keys for controlling the selector mechanism, means operatively related to one of the shafts for automatically returning the sliding member to shift the gear to an inoperating position, and means for manually returning the sliding member independently of the last said means.

31. In a calculating machine, the com-

bination of a pair of shafts, a series of gears connected with one of the shafts for imparting variable movement to one of the shafts, a traveling gear connected with the other shaft and coöperating with the said series of gears, selector mechanism for shifting the traveling gear, said mechanism including a slideable member with which the gear is connected, keys for controlling the selector mechanism, an oscillating member adapted to engage and move the sliding member to shift the traveling gear into an inoperating position, and means operatively related to one of the shafts for moving the said oscillating member.

32. In a calculating machine, the combination of a pair of shafts, a series of gears connected with one of the shafts for imparting variable movement to one of the shafts, a traveling gear connected with the other shaft and coöperating with the said series of gears, selector mechanism for shifting the traveling gear, said mechanism including a slideable member with which the gear is connected, keys for controlling the selector mechanism, an oscillating member adapted to engage and move the sliding member to shift the traveling gear into an inoperating position, means operatively related to one of the shafts for moving the said oscillating member, and means for controlling the movement of the said oscillating member at will.

33. In a calculating machine, the combination of a series of operating shafts, selector mechanisms individual to the shafts for controlling the degree of rotation thereof; said selector mechanism each including a slideable setting member, a plurality of keys individual to each of said members for controlling the movement of the latter in one direction, pivoted means common to all of the members for simultaneously moving the members in the opposite direction, mechanism for controlling the last said means, and means individual to the said members for moving the members in the last said direction independently and at will.

34. In a calculating machine, the combination of a plurality of pairs of coöperating shafts, a series of gears individual to one of the shafts of each pair, a traveling gear individual to the other shaft of each pair, selector mechanisms individual to each of the said traveling gears, each of said mechanisms including a slideable member to which the respective gears are connected for adjustment, a series of keys individual to each of the members for controlling the degree of movement thereof in one direction, pivoted means common to all of said members for simultaneously moving the members in the opposite direction to restore the mechanism to normal position, means operatively related to one of the

shafts for actuating the last said means, and means individual to each of the said sliding members for moving the members in the opposite direction and independently of 5 each other.

35. In a calculating machine, the combination of a plurality of pairs of coöperating shafts, a series of gears individual to one of the shafts of each pair, a traveling gear individual to the other shaft of each pair, selector mechanisms individual to each of the said traveling gears, each of said mechanisms including a slideable member to which the respective traveling gears are connected for adjustment, a series of keys individual to each of the members for controlling the degree of movement thereof in one direction, pivoted means common to all of said members for simultaneously moving 10 the members in the opposite direction to restore the mechanism to normal position, means operatively related to one of the shafts and including clutch mechanism operable at will for actuating the last said 15 means, and means individual to each of the said sliding members for moving the members in the opposite direction and independently of each other.

36. In a calculating machine, the combination of a plurality of pairs of coöperating shafts, a series of gears individual to one of the shafts of each pair, a traveling gear individual to the other shaft of each pair, selector mechanisms individual to each of 30 the said traveling gears, each of said mechanisms including a slideable member to which the respective traveling gears are connected for adjustment, a series of keys individual to each of the members for controlling the 35 degree of movement thereof in one direction, means individual to the sliding members for independently moving the said slideable members to move the respective traveling gears to their normal positions and for 40 restoring the respective actuated key, and additional means common to all of the slideable members for simultaneously moving the latter to restore the traveling gears to normal 45 positions and for restoring the actuated 50 keys of all of the series of keys.

37. In a calculating machine, the combination of an operating shaft, selector mechanism for controlling the operation thereof, keys for controlling the said mechanism, 55 said keys being provided with stems and a projection on each of the stems, said selector mechanism including a slideable member and said member being provided with recesses for receiving the projections 60 on the respective keys, means for holding the member so that the recesses will normally stand in positions to receive the projection on the respective keys when the key

is actuated, and means for shifting the member when one of the projections passes 65 through its recesses in the member to displace the remaining recesses with relation to the projections on the remaining keys to lock the last recited keys against actuation and the actuated key in its actuated position. 70

38. In a calculating machine, the combination of an operating shaft, selector mechanism for controlling the operation thereof, keys for controlling the said mechanism, 75 said keys being provided with stems and a projection on each of the stems, said selector mechanism including a slideable member and said member being provided with recesses for receiving the said projections, a locking member for holding the slideable member in 80 a position that the recesses will be normally positioned to receive the projections on the respective key stems, said member being adapted to be engaged and tripped by any of the keys, and means for shifting the slideable member when the latter is released and the projection on one of the stems passes through its recess in the member to displace all of the recesses with relation to their 85 respective projections to lock the actuated key in its actuated position and the remaining 90 keys against actuation.

39. In a calculating machine, the combination of an operating shaft, selector mechanism for controlling the operation thereof, keys for controlling the said mechanism, 95 said keys being provided with stems and a projection on each of the stems, said selector mechanism including a slideable member and said member being provided with 100 recesses for receiving the said projections, a locking member for holding the slideable member in a position that the recesses will be normally positioned to receive the projections on the respective key stems, said member being adapted to be engaged and tripped by any of the keys, means for shifting the slideable member when the latter is released and the projection on one of the stems passes through its recess in the member to displace 105 all of the recesses with relation to their respective projections to lock the actuated key in its actuated position and the remaining 110 keys against actuation, and means for returning the slideable member to again 115 position the recesses with relation to the respective projections.

In testimony whereof I have signed my name to this specification, in the presence of two subscribing witnesses, on this 14th day 120 of March A. D. 1910.

OTTO MALCHER.
